(57) **CLAIM**

The ornamental design for a housing of a laser processing machine, substantially as shown and described.

DESCRIPTION

FIG. 1 is a perspective view of our laser processing machine housing.

FIG. 2 is a front view of the laser processing machine housing of FIG. 1.

FIG. 3 is a back view of the laser processing machine housing of FIG. 1.

FIG. 4 is a right side view of the laser processing machine housing of FIG. 1.

FIG. 5 is a left side view of the laser processing machine housing of FIG. 1; and,

FIG. 6 is a top view of the laser processing machine housing of FIG. 1.

The broken lines illustrate environmental features that form no part of the claimed design.

1 Claim, 4 Drawing Sheets
